UNITED STATES PATENT OFFICE.

BERTRAND E. BUCKMASTER, OF TACOMA, WASHINGTON.

BANK CHECK AND DRAFT SYSTEM.

No. 911,374.

Specification of Letters Patent.

Patented Feb. 2, 1909.

Application filed May 14, 1906, Serial No. 316,832. Renewed August 20, 1908. Serial No. 449,535.

To all whom it may concern:

Be it known that I, BERTRAND E. BUCKMASTER, citizen of the United States, residing at Tacoma, in the county of Pierce and State 5 of Washington, have invented certain new and useful Improvements in Bank Check and Draft Systems, of which the following is a specification.

My invention relates to that class of books 10 in which bank-checks and a check-record are removably retained in a single binder; and it has for its object to structurally improve such books by the provision of materially advantageous means for effecting detachable connection of both the bank - checks and the 15 check-record to the binder.

Other advantageous features of my invention will be fully understood from the following description and claims when the 20 same are read in connection with the accompanying drawings, forming part of this specification, in which:

Figure 1 is a view of my novel book as the 25 same appears when open and ready for use. Fig. 2 is an enlarged detail section taken in the plane indicated by the line 2—2 of Fig. 1, and illustrating the manner in which a pad of bank-checks is connected to the right-hand cover of the binder. Fig. 3 is a similar view 30 taken in the plane of the line 3—3, Fig. 1, and showing the mode of connecting a pad of check-record sheets to the right-hand cover of the binder, and: Fig. 4 is a section taken in the plane indicated by the line 4—4 of 35 Fig. 1, looking toward the right.

Similar letters designate corresponding parts in all of the views of the drawings, referring to which:

A is the binder of my novel book. B is 40 the pad of bank-checks, and C, the pad of check-record sheets.

As shown in Fig. 1, the binder A comprises a left-hand cover *a*, a right-hand cover *b*, and a flexible back *c* interposed between 45 and connecting the adjacent ends of the said covers. Fixed to and rising from the inner side of the right-hand cover *b*, at points adjacent to the back *c*, are threaded posts *d d* and *e e* which are equipped with thumb nuts *f f* and are designed to serve a purpose presently set forth in detail.

The pad B is made up of a plurality of superposed blank checks *g*, a strip *h*, of suitable textile material, to which the upper 55 edges of the checks are glued and which is provided with the portion *i* extending be-

yond the lowermost check *g*, and a stiff base *j*, of pasteboard or other suitable material, disposed below the lowermost check and connected to the portion *i* of the strip *h*, preferably in the manner shown—*i. e.*, by gluing its underside to the said portion *i* which is lapped over its upper edge, as clearly shown in Fig. 4. The base *j* extends inwardly beyond the inner ends of the superposed checks *g* about the proportional distance illustrated, and is provided in its extended portion *j*¹ with apertures *k* designed to receive the fixed posts *d* on the right-hand cover *b* of the binder A. When the extended portion *j*¹ of the pad base *j* is placed in engagement with the posts *d* as stated, and the thumb nuts *f* complementary to said posts are screwed down tight against the base as shown in Fig. 2, it will be apparent that the pad will be 70 strongly connected to the binder cover *b*. It will also be apparent that the said connection does not entail the provision of apertures in the checks *g* which is an important advantage for reasons hereinafter fully 75 set forth.

The pad C is made up of a plurality of superposed sheets *m* which are preferably though not necessarily punched, as indicated by *n*, so that they may be placed, subsequent 80 to their removal from the pad, in a looseleaf binder or the like, a base *p* of pasteboard or other suitable material disposed below the superposed sheets and extended beyond the inner ends thereof and provided 85 in its extended portion *p*¹ with apertures *r*, and a strip of textile material *s* glued to the upper ends of the sheets *m* and having a portion *t* lapped over the upper edge of the base *p* and glued or otherwise fastened to 90 the underside thereof. The extended portion *p*¹ of the base *p* is designed to be engaged with the posts *e* of the right-hand cover *b* of the binder A, and be held on said posts by the nuts *f* in the manner illustrated, 95 so as to effect connection between the pad and the binder without the provision of post-receiving apertures in any element of the pad other than the base *p*.

It will be apparent from the foregoing 100 that my improvements obviate the necessity of punching the checks, and hence render it feasible to employ checks having no stubs. Such checks may be approximately 105 eight and three-eighths inches long by three and three - eighths inches wide, and are adapted to be cut with no waste whatever 110

which is an important desideratum when the comparatively expensive banker's safety paper is employed in the production of the checks. In other words my novel checks 5 of the approximate size stated cut sixteen out of the standard size sheets of paper which are seventeen by twenty-eight inches. Again, my novel checks of the approximate size stated are susceptible of being lithographed to advantage as will be fully appreciated from the following:

In printing by lithography reproductions are made from the engraving as many times as is practicable according to the size of the 15 order to be run, and it is expedient that one transfer keep a press running—this in order to produce work at competitive prices. With my checks of the size specified, the work can be transferred four on a quarter 20 sheet (8½ x 14 inches) for very small runs, eight on a half sheet (14 x 17 inches) for moderate size runs, and sixteen on a full sheet (17 x 28 inches) for long runs.

I prefer the construction herein shown 25 and described but desire to make it clear that such changes or modifications may be made in practice as fully fall within the scope of my claimed invention without involving departure from the same.

30 Having described my invention, what I claim and desire to secure by Letters Patent, is:—

1. In a book of the kind described, the combination of a binder having posts, a pad 35 comprising a plurality of superposed pieces of paper, and a stiff base, of pasteboard or other suitable material, disposed below and connected to the superposed pieces, and extending beyond the same at one end and 40 having apertures in its extended portion receiving the posts of the binder, and retain-

ing means arranged on the posts above the extended portion of the pad base.

2. In a book of the kind described, the combination with a binder comprising covers 45 and a flexible back interposed between and connecting the covers, and having threaded posts fixed to one of the covers and nuts adjustable on said posts; of a pad comprising a plurality of superposed pieces of paper, 50 and a stiff base, of pasteboard or other suitable material, disposed below and connected to the superposed pieces and extending beyond the same at one end and having apertures in its extended portion receiving 55 the posts of the binder.

3. In a book of the kind described, the combination of a binder comprising covers, a flexible back connecting the covers, and two pairs of threaded posts fixed to and 60 rising from the right-hand cover at points adjacent to the back and equipped with nuts; of a pad arranged on the right-hand cover of the binder and comprising superposed checks and a stiff base disposed below 65 and connected to the checks and extended beyond the same at the left-hand end and having apertures in its extended portion receiving one pair of posts, and a second pad arranged on the right-hand cover and comprising superposed record sheets and a stiff base disposed below and connected to the record sheets and extended beyond the same 70 at the left-hand end and having apertures in its extended portion receiving the other 75 pair of posts.

In testimony whereof I affix my signature in presence of two witnesses.

BERTRAND E. BUCKMASTER.
